UNITED STATES PATENT OFFICE.

THOMAS O. POTTER, OF BOSTON, MASSACHUSETTS.

BUCKLE.

SPECIFICATION forming part of Letters Patent No. 242,475, dated June 7, 1881.

Application filed April 28, 1881. (No model.)

To all whom it may concern:

Be it known that I, THOMAS O. POTTER, of Boston, in the county of Suffolk and Commonwealth of Massachusetts, have invented certain new and useful Improvements in Buckles, of which the following is a full, clear, and exact description, reference being had to the accompanying drawings, forming a part of this specification, in explaining its nature, in which—

Figure 1 is a plan of a blank from which the buckle-frame is formed. Fig. 2 is an elevation of the complete buckle. Fig. 3 is a plan of the buckle. Fig. 4 is a cross-section on the line X X of Fig. 2. Fig. 5 is a perspective of one ear of the buckle. Figs. 6, 7, 8, and 9 are, respectively, an elevation, cross-section, detail, and perspective views of a modification in construction.

This invention has for its object the specific construction herein described, whereby the buckle is easily and cheaply made, and when completed has no points or projections upon which the clothing can catch or be worn.

A is the blank from which the buckle is formed. It is made of some easily-shaped metal, and embraces the body *a*, the hook-forming portion *b*, and the ears *c*; and in each ear is formed a socket, *d*, by the process known as "striking up," and which involves the displacement of the metal by suitable dies, under pressure, without destroying its continuity. With some kinds of metal it may be necessary to temper the ears before striking up the sockets. The sockets open upon the inner side of the ears, and their projections upon the outer side, formed by the striking up, are so well rounded that they do not form what may be

termed "wearing" projections or points, upon which the clothing may catch or wear. The 40 sockets preferably are formed before the ears are bent at right angles to the body, as represented in Fig. 2, although they may be struck up after the ears are bent, if desired.

The jaw *e* and the lever *g* are struck up from 45 a suitably-shaped blank, and may be provided with ears for embracing the pivotal bar *f*, as represented, or may have projecting from each side, as shown in Figs. 6, 7, 8, and 9, the pivots *h*, which project outwardly from the ends 50 of the downwardly or inwardly projecting arms *m*. Whichever method is employed the ends of the bar or pivots *h* fit within the sockets, and the outer surface of the jaw *e* is brought in line with the upper edges or ends of the 55 ears *c*, thereby preventing the ears from becoming sharp isolated projections upon which clothing may wear or be caught.

The advantages of this invention are economy in the use of metal, simplicity and cheapness of construction, and protection of the 60 ends of the pivots or cross-bar by a rounded continuous surface, which prevents their doing any injury to clothing.

Having thus fully described my invention, I 65 claim and desire to secure by Letters Patent of the United States—

The combination, in a buckle, of the frame provided with the sockets *d* with the jaw *e*, supported in such sockets and having its ends 70 entirely inclosed therein, all substantially as shown and described.

THOMAS O. POTTER.
